HONING DEVICE

Joseph Sunnen, Clayton, Mo.

Application August 20, 1943, Serial No. 499,402

9 Claims. (Cl. 51—184.3)

1

This invention relates to honing devices and more particularly to a new and improved mandrel and hone assembly capable of securing maximum accuracy in the finish of the holes and also for the purpose of maintaining evenly balanced pressures on the operating surfaces of the hones.

I have found that the greatest accuracy in finish can be obtained by the use of a hone arbor having two circumferentially spaced hones and a guide, so that the hone arbor assembly has a three point contact with the interior surface of the hole which is being finished.

It might be assumed that with such construction, the two hones and the guide might be spaced at equal intervals of 120° around the circumference as the pressure on each of the hone surfaces would be exactly equal while the hone is stationary in the hole. However, I have found that the hones do not wear evenly as might be expected from an analysis of the forces when the hone is not actually rotating in the work.

I have discovered a method of spacing and locating the hones and the guide in such a manner as to substantially equalize the cutting action of the hones while also obtaining a substantial increase in the accuracy of the finished work.

An object of my invention is to provide a new and improved hone arbor capable of finishing the inside surfaces of holes with greater accuracy than has previously been obtainable.

It is a further object of my invention to produce a new and improved hone arbor assembly which is capable of performing the cutting operation at a maximum rate without sacrifice of accuracy.

It is a further object of my invention to produce a new and improved hone arbor assembly of the type having two circumferentially spaced hones and a guide in which the hones are equally loaded per unit area during operation.

It is a further object of my invention to produce a new and improved hone arbor assembly of the type having two circumferentially spaced hones and a guide in which the rate of wear of the two hones will be substantially uniform.

The invention will be better understood upon reference to the following description and accompanying drawings, referring to which:

Figure 1 is an end view of a hone arbor assembly embodying my invention.

Figure 2 is a side elevation of the hone arbor shown in Figure 1.

Figure 3 is a sectional view of the hone arbor shown in Figure 1, taken along the section line 3—3 of Figure 1.

2

Figure 4 is a sectional view of the arbor taken along section line 4—4 of Figure 3.

Figure 5 is a side elevation of one of the wedge retainer members. This figure is drawn to twice the scale used in the preceding figures.

Figure 6 is an end view of the guide and retainer members shown in Figure 5.

Figure 7 is a plan view of the guide and retainer members shown in Figures 5 and 6.

Figure 8 is a side elevation of the hone shown in Figures 1, 2 and 3, the figure being drawn to twice the scale of said figures.

Figure 9 is a plan view of the hone shown in Figure 8.

Figure 10 is an end view of the hone shown in Figures 8 and 9.

Figure 11 is an inverted plan view of the hone shown in Figures 8, 9 and 10.

Figure 12 is a side elevation of one of the wedge retainers shown in Figures 2 and 3 looking from the rear with respect to Figure 3, drawn to a scale twice that of Figure 3.

Figure 13 is an inverted plan view of the device shown in Figure 12.

Figure 14 is a plan view of the device shown in Figures 12 and 13.

Figure 15 is an inverted side elevation of the wedge member, drawn to twice the scale used in Figures 1, 2 and 3.

Figure 16 is a plan view of the wedge member shown in Figure 15.

The reference numeral 1 indicates a hone arbor suitable for use in any honing machine and particularly adaptable for use in connection with a machine such as shown in my Patent No. 2,070,381. The arbor is provided with a shank 2 having retaining means 3 adapted to fit into and be driven by the spindle of the honing machine. The spindle (not shown) carries a longitudinally

40 slidable member 4 for operating the adjusting cam, and this member extends into a bore 5 in the shank of the arbor, having a coupling member 6 to engage a corresponding coupling member 7 carried by the plug 8 which is slidable in the bore 5. The arbor is provided with longitudinal slots 9 to receive the lugs 10 which are attached to the member 8 by suitable screws 11 in such a manner as to permit longitudinal adjustment by movement of the member 4. The arbor

45 is provided with longitudinal grooves 12 and 13 to receive the hones 14 and the slidable wedge members 15.

The wedges 15 are provided with notches 16 to snugly fit over the lugs 10, so that longitudinal 55 movement of the lugs will result in a correspond-

ing movement of the wedges. The hones are provided with projecting cam members 17 and 18 which are eccentrically spaced with respect to the center of the hone and mounted parallel with each other to cooperate with cam grooves 19 and 20 formed in the wedges 15. The hones and wedges, together, snugly fill the lateral width of the grooves 12 and 13.

The wedges are held against radial movement by the hooks 21 on the retainers 22 and 23, while the hone is permitted to move radially as the wedges are adjusted. This radial movement of the hone is permitted by the coupler slots 24 formed at the ends of the hones to engage corresponding coupler slots 25 on the member 22. While only a single hone in each groove is shown, two or more hones can be coupled together in the same groove by means of the coupling slots, it being understood that additional cam grooves corresponding to the grooves 19 and 20 in the member 15 will be provided where additional hones are to be used.

The hone comprises a metallic support member 14 having an abrasive stick 26 rigidly secured to the upper edge thereof. The construction and arrangement will be fully understood from Figures 8 to 11, inclusive, and it is more fully described and claimed in my copending application Serial No. 427,654, filed January 21, 1942.

Member 23 is held in position in the grooves 12 and 13 by screws extending into the holes 28, suitable holes 29 being formed in the shaft for this purpose. Corresponding screw holes 30 in the member 22 receive screws which are inserted through the holes 31 in the arbor. The member 23 is provided with a recess 32 having a central projection 33 to which is attached a flat spring 34 coiled around the central projection and extending outwardly so as to contact the coupler at the end of the hone. It will be understood that the coupler may extend into the recess and hook into the wall 35 thereof, so that the spring 34 will retain the hone against longitudinal movement with respect to the arbor, if desired.

A third longitudinal groove 36 is formed in the arbor and constructed and arranged to carry one or more suitable guide members 37. These guide members may be formed of metal, plastic, or any material having the desired degree of hardness and co-efficient of friction for the purposes hereinafter to be described. The guide members are held in position by screws 38, the heads of which extend into slots 39 formed in the arbor at the side of the groove 36 as shown in Figure 1. These screws are threaded into the guide members, so that when the screws are tightened, they extend beyond the wall thereof against the opposite wall of the groove as indicated in Figure 1. As the guide wears, it may be raised by inserting one or more shims 40 between the bottom of the groove and the guide.

The angular spacing of the grooves 12, 13 and 36 with respect to each other and the direction of rotation is an important feature of this invention. The direction of rotation of the arbor is counterclockwise with respect to Figure 1 as indicated by the arrow. In order to secure even pressures on the abrasive sticks 26 and 261 operating in the grooves 12 and 13, respectively, the relative co-efficients of friction of the guide 37 and of the abrasive sticks with the material which is being worked on must be taken into consideration. Ordinarily, the guide has a much lower co-efficient of friction than the hones, especially when the grain of the abrasive material is

coarse or when the material being worked on is soft.

In order to secure maximum speed in the removal of metal in the honing operation, it is necessary to have both hones operating at the maximum cutting rate they will stand without causing excessive wear. In order to secure this result, the hones must be equally loaded; that is, the pressure with which they are held outwardly against the inside of the hole must be kept equal. This equality of pressure would be obtained by spacing the hones and the guides at 120° when the hone is stationary, but I have found that a different condition is set up when the hone is in operation.

In operation, the turning action of the hone in the work sets up a moment arm about each contact surface as an axis, and the magnitude of the torque is a function of the outward pressure applied to the hones by the cams, multiplied by a function of the co-efficient of friction of the surface of the guide or hone with the material which is being worked on, and divided by the length of the arm represented by the spacing of the trailing contact surface. This results in the loading of each contact surface by the friction of the sliding surface which precedes it. For instance, in Figure 1, the friction of the hone in the groove 12 increases the load of the hone in the groove 13, while the hone in the groove 13 loads the guide 37 which, in turn, loads the hone in the groove 12. As long as the co-efficient of friction of the guide is lower than that of the hones, the hone 12 will be loaded substantially less than the hone 13 in the groove 13.

I have found that the disadvantages due to uneven loading of the hones can be substantially eliminated by spacing the hones at unequal intervals in such a manner that the moment arm from the leading hone 26 to the trailing hone 261 is increased, while the resultant of the initial load on the hones 261 and 37 is directed more nearly parallel to the center line of the hone 26 than the resultant of the initial load on hone 26 and cam 37 is to the center line of the hone 261.

Obviously, the spacing of the hones and guides in accordance with this principle should theoretically vary with the relative co-efficients of friction of the guide and hone members, and these, in turn, will depend on the coarseness of the hone being used, as well as on other factors. However, I have found that a workable arrangement which is adaptable to most conditions is substantially that shown in the drawings in which the leading hone follows the guide by approximately 135° and the trailing hone follows the leading hone by approximately 140°, leaving 85° between the trailing hone and the guide. It will be understood that the principles, apparatus, and method described herein may be embodied in various ways and that the angles mentioned are merely by way of illustration and are not intended as limitations.

I claim:

1. In a hone arbor assembly, an arbor having a pair of longitudinal grooves therein, said grooves being circumferentially spaced at an angle greater than 120° and less than 180°, hones in said grooves, and non-abrasive guide means carried by said hone arbor at a point angularly spaced from and opposed to said hones in such a position as to balance the working loads applied to the hones in operation.

2. In a hone arbor assembly, an arbor having a pair of longitudinal grooves therein, said

grooves being circumferentially spaced at an angle greater than 120° and less than 180° , hones in said grooves, said arbor being constructed and arranged to normally rotate in one direction, and non-abrasive guide means carried by said hone arbor at a point angularly spaced from and opposed to said hones, said guide means being substantially more distantly spaced from the groove which it follows than from the groove which it precedes in rotation whereby the working loads applied to the hones in operation are balanced.

3. In a hone arbor assembly, a hone arbor, a pair of circumferentially spaced longitudinal grooves in said arbor, similar hones in said grooves, each hone comprising a hone support and an abrasive stick, said hone supports having cam surfaces on a side adjacent the center of the grooves, wedges mounted in said grooves at the side of said hone supports, said wedges having cam surfaces cooperating with the cam surfaces on the respective hones, said wedges being longitudinally slidable in said grooves for the purpose of adjusting said hone, and guide means for adjusting said wedges.

4. In a hone arbor assembly, a hone arbor, a pair of circumferentially spaced longitudinal grooves in said arbor, similar hones in said grooves, each hone comprising a hone support and an abrasive stick, said hone supports having cam surfaces on a side adjacent the center of the grooves, wedges mounted in said grooves at the side of said hone supports, said wedges having cam surfaces cooperating with the cam surfaces on the respective hones, said wedges being longitudinally slidable in said grooves for the purpose of adjusting said hone, guide means for adjusting said wedges, and guide means carried by said arbor at a point opposed to said hones.

5. In a hone arbor assembly, a hone arbor, a pair of circumferentially spaced longitudinal grooves in said arbor, similar hones in said grooves, each hone comprising a hone support and an abrasive stick, said hone supports having cam surfaces on a side adjacent the center of the grooves, wedges mounted in each of said grooves at the side of said hone supports, said wedges having cam surfaces cooperating with the cam surfaces on the respective hones, said wedges being longitudinally slidable in said grooves for the purpose of adjusting said hone, a single adjusting member carried by said arbor, and means connecting said adjusting member with both of said wedges for simultaneous adjustment thereof.

6. In a hone arbor assembly, a hone arbor, a pair of circumferentially spaced longitudinal grooves in said arbor, similar hones in said grooves, each hone comprising a hone support and an abrasive stick, said hone supports having cam surfaces on a side adjacent the center of the grooves, wedges mounted in each of said grooves at the side of said hone supports, said wedges having cam surfaces cooperating with the cam

surfaces on the respective hones, said wedges being longitudinally slidable in said grooves for the purpose of adjusting said hone, a single adjusting member carried by said arbor, and means connecting said adjusting member with both of said wedges for simultaneous adjustment thereof, said hones being spaced circumferentially from each other at an angle greater than 120° and less than 180° , and a single bearing member circumferentially spaced from and opposed to said hones at unequal angles.

7. In a hone arbor assembly, a hone arbor, a pair of circumferentially spaced longitudinal grooves in said arbor, similar hones in said grooves, each hone comprising a hone support and an abrasive stick, said hone supports having cam surfaces on a side adjacent the center of the grooves, wedges mounted in said grooves at the side of said hone supports, said wedges having cam surfaces cooperating with the cam surfaces on the respective hones, said wedges being longitudinally slidable in said grooves for the purpose of adjusting said hones, control means for adjusting said wedges, said hones being spaced circumferentially from each other at an angle greater than 120° and less than 180° , and guide means carried by said arbor at a point opposed to said hones, said guide means being eccentrically spaced with respect to said hones.

8. In a hone arbor, a pair of circumferentially spaced hones located on one side of a plane containing the axis of the arbor, and a non-abrasive guide located on the other side of said plane, said guide and said hones being similarly positioned with respect to the axis of said arbor so that their working surfaces would rotate in the same cylindrical path.

9. In a hone arbor, a pair of circumferentially spaced hones located on one side of a plane containing the axis of the arbor, and a non-abrasive guide located on the other side of said plane, said guide and said hones being similarly positioned with respect to the axis of said arbor so that their working surfaces would rotate in the same cylindrical path, the angular position of said hones being differentially spaced with respect to said guide.

JOSEPH SUNNEN.
